COMBINED POCKET LIGHTER, LEVEL AND COMPASS

Elwood W. Grushon, 3731 S. Sepulveda Blvd.,
Los Angeles, Calif.

Filed Sept. 28, 1962, Ser. No. 71,922

Term of patent 3½ years

(Cl. D48—27)

Fig. 3

Fig. 1

Fig. 2

Fig. 4

FIG. 1 is a front elevational view of a combined pocket lighter, level and compass showing my new design;
FIG. 2 is a right side elevational view thereof;
FIG. 3 is a left side elevational view, and
FIG. 4 is a top perspective view.
The undisclosed rear and bottom are substantially flat and plain.

I claim:

The ornamental design for a combined pocket lighter, level and compass, substantially as shown and described.
